UNITED STATES PATENT OFFICE.

NAPOLEON DU BRUL, OF CINCINNATI, OHIO.

DESIGN FOR A CIGAR-WRAPPER CUTTING AND ROLLING TABLE.

SPECIFICATION forming part of Design No. 35,521, dated December 31, 1901.

Application filed May 29, 1901. Serial No. 62,441. Term of patent 14 years.

To all whom it may concern:

Be it known that I, NAPOLEON DU BRUL, a citizen of the United States, and a resident of Cincinnati, in the county of Hamilton and State of Ohio, have invented and produced a new and original Design for a Cigar-Wrapper Cutting and Rolling Table, of which the following is a full, clear, and exact specification, reference being had to the accompanying drawings, forming part thereof, in which—

Figure 1 is a plan, and Fig. 2 is a front elevation, of a cigar-wrapper cutting and rolling table embodying my new design.

As shown in said drawings, the leading and material features of my new design are, first, a substantially rectangular rolling-table; second, a rectangular box or chamber located at the front side of and upon said table and of less lateral dimension than said table, so as to leave spaces on the surface of the table at the sides and back of the box or chamber, and,

third, a narrow oblong raised block formed with a semicylindrical longitudinal groove in its upper face and fixed near an inner corner of the rectangular box or chamber in an approximately diagonal position on the table and extending from near one side of the table within the space at the side of the box or chamber inwardly and rearwardly from said side. 25

Having thus described my design, I declare that what I claim as new therein, and desire to secure by Letters Patent, is—

The design for a cigar-wrapper cutting and rolling table, substantially as herein shown 35 and described.

The foregoing specification signed this 18th day of May, 1901.

NAPOLEON DU BRUL.
